UNITED STATES PATENT OFFICE.

MICHEL DUBOST, OF PARIS, FRANCE, ASSIGNOR TO F. DUCHARNE SILK CO. INC., OF NEW YORK, N. Y., A CORPORATION OF NEW YORK.

DESIGN FOR A TEXTILE FABRIC.

Application filed November 30, 1926. Serial No. 19,886. Term of patent 3½ years.

To all whom it may concern:

Be it known that I, MICHEL DUBOST, a citizen of France, residing in Paris, France, have invented a new, original, and ornamental Design for a Textile Fabric, of which the following is a specification, reference being had to the accompanying drawing forming part thereof.

The figure is a plan view of a textile fabric showing my new design.

I claim:

The ornamental design for a textile fabric substantially as shown.

MICHEL DUBOST.
